PNEUMATIC LIFT

William C. Albertson, Cleveland, Ohio, assignor to Life Time Products Corp., Los Angeles, Calif., a corporation of California

Application February 10, 1958, Serial No. 49,562

Term of patent 14 years

(Cl. D41—1)

Fig. 3.

Fig. 4.

Fig. 1 is a perspective view of a pneumatic lift showing my new design, the same being in its lowered position. Fig. 2 is a similar view showing the lift raised.

Fig. 3 is a side elevational view of the pneumatic lift as seen from the side opposite to Fig. 1.

Fig. 4 is a longitudinal sectional view as seen from the same side.

Fig. 5 is a fragmentary perspective view of a detail of the design, the same being an enlargement of the left end portion of the lift as in Fig. 3.

I claim:

The ornamental design for a pneumatic lift, substantially as shown.
